(57) **CLAIM**

The ornamental design for a compact, as shown.

DESCRIPTION

FIG. 1 is a top, front and right side perspective view of our new design for a compact;

FIG. 2 is a bottom, front and right side perspective view of the compact shown in FIG. 1;

FIG. 3 is a top plan view of the compact shown in FIG. 1; FIG. 4 is a bottom plan view of the compact shown in FIG. 1; FIG. 5 is a front elevation view of the compact shown in FIG. 1;

FIG. 6 is a rear elevation view of the compact shown in FIG. 1;

FIG. 7 is a left side elevation view of the compact shown in FIG. 1;

FIG. 8 is a right side elevation view of the compact shown in FIG. 1; and,

FIG. 9 is a front and right side perspective view of the compact shown in FIG. 1 in the open position.

The broken lines illustrate portions of the compact. The broken lines and the unshaded portions within form no part of the claimed design.
